T. L. DONAHIE,
VALVE FOR HOT BLAST STOVES.
APPLICATION FILED JULY 11, 1917.

1,258,661.

Patented Mar. 12, 1918.

UNITED STATES PATENT OFFICE.

THOMAS L. DONAHIE, OF WHEELING, WEST VIRGINIA.

VALVE FOR HOT-BLAST STOVES.

1,258,661.

Specification of Letters Patent. Patented Mar. 12, 1918.

Application filed July 11, 1917. Serial No. 179,964.

To all whom it may concern:

Be it known that I, THOMAS L. DONAHIE, a citizen of the United States, and resident of Wheeling, in the county of Ohio and 5 State of West Virginia, have invented certain new and useful Improvements in Valves for Hot-Blast Stoves, of which the following is a specification.

My invention relates to the construction 10 and arrangement of the valves forming part of the equipment of hot-blast stoves, and the invention more particularly relates to the construction and arrangement of a combined chimney and blow-off valve for use 15 on hot blast stoves.

One object of this invention is to provide a novel combination of valves for use with hot-blast stoves.

Another object of my invention is to provide 20 means for preventing the excessive noise heretofore made in relieving the air pressure in such hot-blast stoves in preparation for burning gases in the stoves to re-heat the stove checkerwork.

25 A further object of my invention is to provide a hot-blast stove having novel means whereby the compressed air remaining within the stove after each blast or air heating operation is released, and the pressure of the 30 air confined within the stove after each air or blast heating operation, is lessened and reduced to that of the atmosphere.

A still further object of my invention is the provision on a hot-blast stove of the 35 novel constructions, combinations, and arrangement of parts shown in the drawings, to be fully described hereinafter and to be particularly pointed out in the appended claims.

40 The hot-blast stoves are regenerative, blast furnace gases being burned in the stove combustion chamber, and the products of combustion passing through the stove checkerwork in their travel to the stove 45 chimney through which the burned gases are discharged into the atmosphere at a considerable elevation above the ground level. The "cold blast" or compressed air is then forced through the stove, generally in the 50 opposite direction, the two operations not occurring at the same time.

While not limited to such use, my invention is particularly adapted for use on hot-blast stoves of the Massicks and Crookes

type, wherein the chimney is supported on 55 and connected to the interior of the stove at the top or upper end of the stove.

Heretofore it has been the practice to 60 position the chimney valve at a point adjacent to that at which the chimney is connected to the interior of the stove. And, so far as I am aware, heretofore, it has been the universal practice to position the air relief or blow-off valve of hot-blast stoves at 65 a point adjacent to the ground level.

When a given quantity of cold blast is 70 introduced into the stove to be heated, and after being heated is caused to pass from the stove into the hot-blast main, the stove checkerwork will have given up so much of its heat to the air that it must again be heated. Thereupon the hot-blast and cold-blast valves on the stove are closed as a preliminary to again heating the stove checkerwork, and, as all other openings into the 75 stove including that closed by the chimney valve have been tightly shut while heating the air blast, the stove remains full of air which is compressed to a pressure of from 80 15 to 35 pounds per square inch. Therefore, it is necessary to lessen the pressure of the air confined within the stove and reduce it to atmospheric pressure before the combustible blast furnace gases can be again 85 applied to the stove in order to again heat the stove checkerwork to the required high 90 temperature.

The chimney valve on such stoves is comparatively large, in the particular case 95 shown being about 48 inches effective diameter, and as the valve moves inwardly in opening, it will be readily seen that a very considerable force is required in order to open the chimney valve against the 15 to 35 pounds air pressure within the stove. Heretofore, a small air relief valve, located 100 at the bottom of the stove near the floor level, has been employed, this valve being opened to relieve the high air pressure within the stove and, by permitting the confined air to escape into the atmosphere, to reduce the air pressure within the stove to that of the atmosphere. When this air relief valve is first opened the compressed air confined 105 within the stove rushes forth with a terrific roar, and the valve being small, so as to permit of its being readily opened, some little time elapses before the pressure in the

stove is reduced to that of the atmosphere, so that the noise caused by the escaping air continues for some time.

With my novel construction and arrangement of valves the relief valve is combined with the chimney valve so that when reducing the air pressure within the stove after each air blast heating operation, the escaping air is discharged into and through the stack on top of the stove, at an elevation of 100 or more feet, and as the stack is 50 to 60 feet higher than the stove the excessive amount of noise heretofore caused by the escaping air is prevented or muffled so that its escape is not audible, does not create any annoyance or disturbance, and lessens the danger to workmen in the immediate vicinity of the stove.

By combining the relief valve and chimney valve, the cost of equipping and maintaining the stove in operation is materially reduced, and by my novel arrangement of valves within the chimney or stack of the hot-blast stoves, the valves are automatically maintained in closed position and are readily operated in opening and closing from any convenient point at the ground level.

In the accompanying drawings, forming part of this specification, Figure 1 is a sectional elevation showing the upper end of a hot-blast stove and lower end of the stove chimney or stack with a combined chimney valve and air-relief or blow-off valve constructed and arranged and applied for use thereon, in accordance with my invention.

Fig. 2 is a sectional elevation on a larger scale, showing details in the construction of my improved valve and valve operating mechanism, the section being taken on the line II—II of Fig. 1.

Fig. 3 is a sectional elevation taken on the line III—III of Fig. 1, showing a detail in the construction of the valve operating mechanism.

In the accompanying drawings, the numeral 2 designates the metal shell of a hot-blast stove of the Massicks and Crookes type; having a combined blow-off and chimney-valve, constructed and arranged and applied for use thereon in accordance with my invention. The stove shell which has the usual refractory lining 3 is provided with checkerwork and a vertical, axially central combustion chamber. Mounted on top of the stove shell 2 is the metal shell of the stove stack or chimney which also has a refractory lining 5, and removably secured in the stack 4 at the base thereof is a removable chimney valve seat 6 and mushroom chimney valve 7. The construction of the valve seat in itself is old.

In my improved apparatus the valve 7 has a central opening 8 therein which forms the blow-off or air-relief outlet for the stove,

and secured in position on the vertical axis of the chimney valve is a puppet valve 9 forming the air-relief or blow-off valve, which is arranged to co-act with and close the blow-off outlet 8 in the chimney valve 7. 70

The stove 2 is provided with the usual cold-blast inlet formed of an elbow 10 which opens upwardly so that in entering the stove the cold-blast will strike against the metal surface of the chimney valve 7 to change its 75 direction of flow and in this way avoid the highly compressed incoming air from striking against the brick work 11 forming the refractory lining in the lower section 12 of the chimney 4 and the dome-shaped partition 13 above the stove combustion chamber.

The stove 2 is provided with lugs 90 14, 14 on its upper surface by which it is pivotally connected to the links 15, 15 from which it is suspended, the upper end of these links 15 being connected to the swinging end of the valve lever 16. This valve 95 lever 16 is pivoted at an intermediate point in its length by a pivot pin 17 to a bracket 18 which is fastened to the adjacent outer surface of the stove stack 4, the lever projecting through a slot or opening 19 provided in the shell and lining of the stack 100 for that purpose.

The outer end of this lever 16 is provided with a counter weight 20 which is adjustably secured thereon, and its outer 105 swinging end has a clevis 21 thereon by which a wire rope or other flexible connection 22 is fastened to the lever, this flexible connection depending downwardly to a point where it is easily grasped by an operator, so that by pulling on the flexible connector the valve 7 will readily close. 110

It will be understood that the counter-weight 20 on the end of the lever 16 is positioned in a manner which will only partly 115 counter-balance the weight of the valve 7 so that this valve will open by gravity when the air is at about atmospheric pressure within the hot-blast stove. Of course, when the air-blast is passing through the stove 120 to be heated, its high pressure forces the valve upwardly and holds it firmly on its seat 6 so as to prevent leakage of air from the stove 2 into the chimney 4 while heating the blast. 125

The puppet valve 9 forming the air-relief valve is removably secured on one end of a stem 23. The upper end of this stem is pivotally connected to the lower end of the links 24, 24, and the upper ends of the links 130

24 are pivotally connected to an intermediate point in the length of the swinging lever 25. This lever 25 is pivotally connected at one end by a pin 26 to one end of the chimney valve operating lever 16 (see Fig. 1). The air-relief valve lever 25 also extends through the slot or opening 19 in the side wall of the chimney or stack 4 and it is provided with a cable or other flexible connection 27 on its outer swinging end which extends downwardly into position to be grasped by an operator.

The puppet valve lever 25 also is pivotally connected by links 28, 28 to one end of a counter-weight lever 29, and this lever is pivoted by a pin 30 on arms 31 which are rigidly secured on the lever 16 for the chimney valve. The lever 29 has a counter-weight 32 which is adjustably secured on one end thereof so as to yieldingly maintain the puppet valve 9 in closed position on its seat in the chimney valve 7 at all times except when it is positively moved into open position through the medium of the rope 27 and lever 25. It will be noted that the operating lever 25 for the puppet air-relief valve 9 being pivotally connected to one end of the swinging lever 16 for the chimney valve 7, the counter-weight 32 will maintain the air-relief valve 9 in closed position in all positions into which the chimney valve 7 is moved, except when the valve 9 is held in open position by means of the flexible cable 27 connected to the outer end 35 of the air-relief valve lever 25.

The pivot support 30 for the counter-weight lever 29 is made to extend downwardly below the lever 16 to which it is rigidly fastened so as to form a guide for 40 the movable puppet valve lever 25.

The operation of my improved apparatus will be readily understood. When the hot-blast stove is "on air," i. e., when the cold-blast is being passed through the stove 2 45 in order to be heated therein the chimney valve 7 and puppet or air-relief valve 9 will be in the closed position shown in Fig. 1.

After the stove has been "on blast" i. e., has been in use for such time interval as is 50 required for heating the checkerwork, the cold-blast valve on the cold-blast main leading to the elbow 10 is closed, and the hot-blast valve on the stove is closed to prevent the hot-blast flowing backwardly from the 55 hot-blast main into the stove when the air within the stove is reduced to atmospheric pressure.

After the hot and the cold-blast valves have been closed, the operator then opens 60 the puppet relief valve 9 by pulling on the cable 27 connected to the outer end of the lever 25, this operation moving the valve 9 downwardly against the pressure of the air now confined within the cold-blast stove 2.

65 As the air within the stove is at 15 to

35 pounds pressure per square inch, considerable force is necessary to open even the small relief valve 9, but by my novel arrangement of levers the necessary force or power is readily obtained.

As soon as the valve 9 begins to open the force required to completely open it is quickly lessened. When the puppet valve 9 is opened the air under pressure within the stove then rushes through the air-relief outlet 8 in the body of the valve 7 and is discharged into the chimney 4, the air passing from the stove into the chimney until the air is reduced to the atmospheric pressure within the stove.

Thereupon the chimney valve automatically opens as it is arranged to over-balance the counter-weight 20, the weight of the cable 22 and the weight of the operating lever 16 for this valve.

The air and gas inlets at the bottom of the stove are then opened and the combustible gases are again delivered into the stove combustion chamber where they are burned to again heat the stove checkerwork to the 90 desired high temperature. The waste gases or products of combustion pass from the combustion chamber through the checker-work and eventually pass into the atmosphere through the stack 4, the stack being 95 of a height sufficient to create the necessary draft through the stove.

When the stove checkerwork is again heated the cable 22 on the end of the chimney valve lever is pulled by the operator 100 so as to close the chimney valve on its seat, and if necessary the cable is fastened to hold the valve in closed position until the cold-blast is turned on.

The openings in the bottom of the stove 105 are then tightly closed after which the valve on the cold-blast main is opened to admit cold-blast into the stove, the cold-blast passing into the stove through the elbow 10 at the upper end of the stove.

The valve on the hot-blast main is then opened so that the air-blast as it becomes heated passes from the stove into the hot-blast main and through the hot-blast main to the bustle pipe, pen-stocks and twyvers, 115 and finally into the blast furnace.

The advantages of my invention, which will be readily appreciated by those skilled in the art, arise from the novel combination and location of parts which are shown and have been described, and which are particularly pointed out in the appended claims.

Instead of having the blow-off or air-relief valve at the bottom of the stove, it opens into the stove stack or chimney, and as the top of the chimney extends for a considerable distance above the ground level, the danger and annoyance caused by the roar of the escaping air when relieving the pressure in the stove is moved to a remote point 130

- where it is not heard, or at least is very indistinct. The liability of injury to workmen caused by the air-blast blowing cinder and other solids on the ground adjacent to the bottom of the stove is avoided and overcome. By combining the air-relief valve and chimney valve, the cost of the apparatus is lessened because the number of parts is reduced.
10. Modifications in the construction and arrangement of the parts may be made without departing from my invention. So far as I am aware, I am the first to locate the blow-off or air-relief valve of a hot-blast stove so that it will discharge into the stack of the stove, and I intend to cover such combination broadly.
- I claim:
1. In the operation of hot-blast stoves, the step of directing into the chimney of the stove the heated air under pressure trapped in the stove preparatory to reheating the stove checkerwork.
  2. In the operation of hot-blast stoves, the steps of stopping the blast heating operation by closing the hot-blast valve and cold-blast valve, and then establishing a communication between the interior of the stove and the chimney preparatory to reheating the stove checkerwork, whereby the heated air under pressure trapped in the stove may escape into the chimney.
  3. A hot-blast stove provided with a valve controlled outlet forming means for directing into the chimney of the stove the heated air under pressure trapped in the stove preparatory to reheating the stove checkerwork.
  4. A hot-blast stove provided with a chimney valve and also having a valve controlled outlet forming means for directing into the chimney of the stove the heated air under pressure trapped in the stove preparatory to opening the stove chimney valve and reheating the stove checkerwork.
  5. The combination with a hot-blast stove, of a chimney out of communication therewith during the heating of air therein, and an air relief outlet to establish communication between the interior of the stove and the chimney for directing into the chimney the heated air under pressure trapped in the stove preparatory to reheating the stove checkerwork.
  6. A hot blast stove provided with a chimney valve having a valve-controlled blow-off opening therethrough.
  7. A hot blast stove provided with a chimney valve having a blow-off opening therethrough, a valve controlling the blow-off opening, and means accessible at the exterior of the stove for controlling the blow-off valve.
  8. A hot blast stove provided with a chimney valve having a blow-off opening there-
- through, a valve for controlling the blow-off opening, a chimney valve lever accessible from the exterior of the stove, and a blow-off valve lever accessible at the exterior of the stove.
9. A combined chimney valve and blow-off for hot blast stoves comprising a chimney valve provided with a blow-off opening and a displaceable closure therefor.
10. In a hot-blast stove, the combination with a chimney connected to the interior of the stove, and a chimney valve for closing said opening, of a valve controlled blow-off opening located in said chimney valve and arranged to connect the interior of the stove with said chimney.
11. In a hot-blast stove, the combination with a chimney connected to the interior of the stove, and a chimney valve for closing said opening, of a valve controlled blow-off opening located in said chimney valve and arranged to connect the interior of the stove with said chimney, and means accessible on the exterior of said stove for controlling said blow-off valve.
12. In a hot-blast stove, the combination with a chimney connected to the interior of the stove, and a chimney valve for closing said opening, of a valve controlled blow-off opening located in said chimney valve and arranged to connect the interior of the stove with said chimney, and means accessible on the exterior of said stove for positively moving said blow-off valve.
13. In a hot-blast stove, the combination with a chimney connected to the interior of the stove, and a chimney valve for closing said opening, of a valve controlled blow-off opening located in said chimney valve and arranged to connect the interior of the stove with said chimney, a chimney valve lever and a blow-off lever, said levers being accessible on the exterior of said stove.
14. In a hot-blast stove, the combination with a chimney connected to the interior of the stove, and a chimney valve for closing said opening, of a valve controlled blow-off opening located in said chimney valve and arranged to connect the interior of the stove with said chimney, a chimney valve lever fulcrumed intermediate of its ends and extending through the wall of the chimney, a link connection between the lever and the chimney valve, a blow-off valve lever fulcrumed on the chimney valve lever and accessible on the exterior of the stove, and a connection between the blow-off valve and its lever.
15. In a hot-blast stove, the combination with a chimney connected to the interior of the stove, and a chimney valve for closing said opening, of a valve controlled blow-off opening located in said chimney valve and arranged to connect the interior of the stove with said chimney, a chimney valve lever

- fulcrumed intermediate of its ends and extending through the wall of the chimney, a link connection between the lever and the chimney valve, a blow-off valve lever fulcrumed upon the chimney valve lever and accessible on the exterior of the stove, a link connection between the blow-off valve and its lever, a bracket carried by the chimney valve lever, a weighted lever mounted upon the bracket, and a link extending between the weighted lever and the blow-off valve lever.
16. In a hot-blast stove, the combination with a chimney connected to the interior of the stove, and a chimney valve for closing said opening, of a valve controlled blow-off opening located in said chimney valve and arranged to connect the interior of the stove with said chimney, means for opening the blow-off valve, and means for yieldably maintaining the blow-off valve seated.
17. In a hot-blast stove, the combination with a chimney connected to the interior of the stove, and a chimney valve for closing said opening, of a valve controlled blow-off opening located in said chimney valve and arranged to connect the interior of the stove with said chimney, means for opening the blow-off valve, and yielding means for automatically moving the blow-off valve into closed position.
18. In a hot-blast stove, the combination with a chimney connected to the interior of the stove, and a chimney valve for closing said opening, of a valve controlled blow-off opening located in said chimney valve and arranged to connect the interior of the stove with said chimney, a lever for opening the blow-off valve, and a tension device associated with the lever for yieldably maintaining the blow-off valve in closed position.
19. In a hot-blast stove, the combination with a chimney connected to the interior of the stove, and a chimney valve for closing
- said opening, of a valve controlled blow-off 45 opening located in said chimney valve and arranged to connect the interior of the stove with said chimney, a lever for opening the blow-off valve, and a tension device associated with the lever for yieldably maintaining the blow-off valve closed, said tension device including a weighted lever mounted independently of the blow-off valve lever and connected thereto.
20. In a hot-blast stove, the combination 55 with a chimney connected to the interior of the stove, and a chimney valve for closing said opening, of a valve controlled blow-off opening located in said chimney valve and arranged to connect the interior of the stove 60 with said chimney, a chimney valve lever fulcrumed intermediate of its ends, a blow-off valve lever fulcrumed at one end to one end of the chimney valve lever, said levers projecting outwardly through an opening 65 in the wall of said chimney, and operating means connected to the outwardly projecting ends of said levers.
21. In a hot-blast stove, the combination 70 with a chimney connected to the interior of the stove, and a chimney valve for closing said opening, of a valve controlled blow-off opening located in said chimney valve and arranged to connect the interior of the stove with said chimney, a chimney valve lever 75 fulcrumed intermediate of its ends, a blow-off valve lever fulcrumed at one end to one end of the chimney valve lever, said levers projecting outwardly through an opening 80 in the wall of said chimney, valve closing means connected to the outwardly projecting end of said chimney valve lever, and valve opening means connected to the outwardly projecting ends of said blow-off valve.

In testimony whereof I have hereunto set my hand.

THOMAS L. DONAHIE.
